UNITED STATES PATENT OFFICE

ELLIOT FOREST RUIHLEY, OF TOLEDO, OHIO

PIPE SYSTEM FOR HOT-AIR HEATING

Application filed November 13, 1928. Serial No. 319,066.

This invention relates to a pipe system for hot air heating adapted particularly for residential installations.

The primary object of the invention is to provide a single conduit leading from the heater in the cellar which is hereinafter referred to as "a central riser". This communicates with a suspended distribution chamber located below the first floor and having branches leading therefrom into the rooms of the first and second floors respectively as hereinafter described.

Another object of the invention is to provide the distribution chamber with a series of baffles which may be independently adjusted and thus proportion the relative amount of air led through the various branches to the different rooms of the house.

Numerous additional objects of a subordinate nature will be apparent to those skilled in the art from a reading of the following specification taken in conjunction with the drawings attached hereto and forming a part hereof.

Figure 1 is a vertical section of a house with my heating system applied thereto;

Fig. 2 is a sectional view taken on line 2—2 of Fig. 1;

Fig. 3 is a cross sectional view taken on line 3—3 of Fig. 1;

Fig. 4 is a similar view taken on line 4—4 of Fig. 1;

Fig. 5 is a sectional view taken on line 5—5 of Fig. 1;

Fig. 6 is a detailed view of the distribution chamber and laterals, while

Fig. 7 is another detailed view, in section, of the distribution chamber.

Referring now to the drawings wherein like reference characters indicate like parts, 1 represents a heater of conventional style having a pipe portion 2 thereover communicating with a central riser 3 passing through an opening in the floor 4 and extending alongside the wall 5. This central riser communicates at its upper extremity with what is hereinafter termed a distribution chamber 6 extending laterally through the wall 5 and suspended just below the first floor ceiling. Sufficient space is allowed by a drop ceiling

below the first floor ceiling for this distribution chamber which may be in a closet, hallway or other convenient location where the ordinary head room is not necessary. From the invention so far described it will be apparent that the multiplicity of pipes ordinarily used in the basement are dispensed with, with the attendant fire hazards when such pipes are placed in a horizontal position in close proximity to the wood construction. Obviously the central riser may be insulated and inasmuch as the flow of heat in a gravity system is naturally upwardly the central riser is a natural outlet. For the purpose of heating the first floor rooms I provide what are termed "laterals" 7 and 8 which are secured to the distribution chamber near the lower portions thereof and extend to, for instance, the living room and the kitchen. The distribution chamber is further provided with upwardly and horizontally extending laterals 9 and 10, preferably positioned at diametrically opposed points as shown in detail in Fig. 6. By this arrangement it will be seen that the laterals for the first floor discharge into the first floor rooms near the ceiling therefor while the laterals for the second floor rooms discharge into the second floor rooms near the second floor.

The distribution chamber is preferably provided with baffles generally indicated by reference numerals 11, 12, 13 and 14 which if desired may be selectively adjusted to proportion the amount of heat desired to enter any particular portion of the house into which a given lateral discharges. As shown I further make provision for the return of cold air to the furnace by providing a passage surrounding the central heat riser illustrated generally by reference numeral 15.

From the foregoing it will be apparent that the invention comprehends particularly the use of an elevated distribution chamber of substantial size communicating with a single riser for receiving hot air from the furnace, which distribution chamber is located under the second floor ceiling and all of the laterals therefrom feeding both floors, thus avoiding substantial heat losses and a multiplicity of

cumbersome pipes ordinarily used with such systems.

Having thus described my invention, what I claim is:

- 5 1. A hot air heating system of the character described comprising a heater, a central riser communicating therewith for conveying upwardly the hot air, a distribution chamber supported immediately below the first floor ceiling, a plurality of laterally extending conduits communicating with the distribution chamber and discharging into the first floor rooms near the ceiling thereof and a series of additional conduits communicating with 10 the distribution chamber and extending upwardly and thence outwardly and discharging into the second floor rooms near the floor thereof.
2. A hot air heating system of the character herein described, comprising a heater, a central riser communicating therewith for conveying upwardly the hot air, a laterally extending distribution chamber supported below the second floor of a building and positioned in close proximity to said floor, a plurality of relatively short laterals leading from the distribution chamber and discharging into the first floor rooms near the ceiling thereof and a plurality of additional laterals 25 secured to the distribution chamber and extending upwardly and thence outwardly and discharging into the second floor rooms near the floor thereof.
3. A hot air heating system for houses comprising a heater, a central riser communicating therewith and extending substantially to the ceiling of the first floor of the house, a horizontally disposed distribution chamber secured at one end to the central riser and extending laterally therefrom and supported immediately adjacent the ceiling of the first floor and lateral hot air conduits communicating with the distribution chamber and discharging into the first floor rooms adjacent 30 the ceiling thereof and into the second floor rooms adjacent the floor thereof respectively.
4. A hot air heating system of the character described, comprising a furnace, a central riser having a portion thereof surrounding the furnace for collecting and discharging hot air upwardly through the central riser, said central riser terminating just short of the second floor ceiling, a distribution chamber, said central riser discharging 35 into the distribution chamber, laterals communicating with the distribution chamber substantially at the ends thereof and discharging into the first floor rooms near the ceiling thereof, and a plurality of additional laterals intermediate the ends of the distribution chamber and extending upwardly and thence horizontally and discharging into the second floor rooms near the floor thereof.

In testimony whereof I affix my signature.

ELLIOT FOREST RUIHLEY.
